UNITED STATES PATENT OFFICE.

CLYDE J. COLEMAN, OF NEW ROCHELLE, NEW YORK, ASSIGNOR, BY MESNE ASSIGNMENTS, TO STERN-COLEMAN DIAMOND MACHINE COMPANY, INC., A CORPORATION OF NEW YORK.

GEM-POLISHING MACHINE.

1,173,175.

Specification of Letters Patent. Patented Feb. 29, 1916.

Application filed November 25, 1912. Serial No. 733,422.

To all whom it may concern:

Be it known that I, CLYDE J. COLEMAN, a citizen of the United States, residing at New Rochelle, in the county of Westchester and 5 State of New York, have invented a certain new and useful Improvement in Gem-Polishing Machines, of which the following is a specification, reference being had thereto in the accompanying drawings, forming 10 part thereof.

My invention relates to machines for grinding and polishing diamonds and other gems, and general objects of my invention are accuracy, celerity and reliability of operation, facility of manipulation, and simplicity, rigidity and durability of construction.

A more specific object of my invention is to provide a device whereby facets of various areas may be polished with equal celerity.

Another object is to obviate skill and prevent scratching of the polishing lap in applying the gem to the lap.

Another object is to provide tripping devices for both a depth gage mechanism and a reciprocatory mechanism, which will be operated by engaging the lap and which will be so arranged that they will not be differentially effected from the gem by unevennesses upon the lap.

Another object is to provide for easy and convenient disengagement of the gem-holding head from its support.

Still other objects and advantages of my invention will appear from the following description.

My invention comprehends variable pressure-applying means arranged to press the 40 gem against the lap with a force increasing in proportion to the increase in area of the facet as the gem is polished, and specifically comprising weighted levers connecting the supporting spindle for the dop-holding head 45 with the spindle-supporting member and operative to rotate from a vertical position as the gem is polished off, thereby applying pressure to draw the spindle down through its support toward the lap.

My invention further comprehends a 50 check device, specifically a dash pot, ar-

ranged to check the rapidity of movement of the gem toward the lap, thereby obviating skill in applying the gem to the lap.

My invention also comprehends the arrangement of a depth-gage trigger and a reciprocatory-means-operating trigger in radial alinement, or side by side, so that both may track in the path of the gem upon the lap.

My invention also comprehends an angularly movable support for these triggers, adjustable angularly about the gem-holding head to bring the triggers into tracking alinement with the gem, and a spring clamp 65 frictionally clamping the trigger support to the gem-holding head and including a pointer coöperating with an index carried by the gem-holding head.

My invention comprehends various other 70 features of construction, and arrangements and combinations of parts, as will herein-after more fully appear.

I shall now describe the embodiment of 75 my invention illustrated in the accompanying drawings, and shall thereafter point out my invention in claims.

Figure 1 is a side elevation of a complete machine embodying my invention, with the supporting table in section and the lap partially in section. Fig. 2 is a plan of the 80 same. Fig. 3 is an enlarged vertical section of the same on line 3—3 of Figs. 1 and 2 looking toward the left and showing the gem-holding head in side elevation with the 85 dop-holding head broken off, the lap and table being omitted. Fig. 4 is a detail in further enlarged central section of the check device. Fig. 5 is a transverse section of the same on line 5—5 of Fig. 4, looking down. 90 Fig. 6 is a transverse section of the same on line 6—6 of Fig. 4, looking up. Fig. 7 is an elevation partly in vertical section of the gem-holding head, drawn to the scale of Fig. 3. Fig. 8 is a transverse section of the 95 same on line 8—8 of Fig. 7, looking down. Fig. 9 is a transverse section of the same on line 9—9 of Fig. 7, looking up. Figs. 10 and 11 are, respectively, a plan and a side elevation of the index plate. Figs. 12 and 100 13 are, respectively, a plan and side elevation of the spring clamp.

The illustrated embodiment of my invention has a disk shaped rotative lap 1 rigidly mounted upon a vertical shaft 2, which bears in the table 3 of the machine and to which power is applied in any suitable way. The upper or the polishing surface of the lap is coated with diamond dust or other suitable abrasive, as is usual.

To hold the gem 4 which is being polished in contact with the polishing surface of the lap 1, a dop-holding head is provided on the lower end of a vertical spindle 5. This supporting spindle is crooked at its lower end to provide a horizontally extending supporting arm on which is provided a slotted arcuate supporting guide 6 for the dop-holding head in a vertical plane coincident with the axis of the spindle 5, arranged to support the dop-holding head upon the upper side of this arcuate guide. This guide has its center coincident with the geometric center of the gem and disposed in the axial line of the spindle 5, and this feature embodies my invention described and claimed in my co-pending application Serial Number 733,417, filed on even date herewith.

The dop consists of a tubular spindle portion 7 and an enlarged tapered dop head 8 provided with a longitudinal bore for receiving the gem arbor 9. This arbor is provided with a longitudinal slot, as shown in Fig. 7, and a set screw 10 in the dop head is arranged to screw into this slot and hold the arbor against relative rotation. A sleeve member 11 surrounds the dop spindle 7 and extends downwardly through the slotted arcuate guide 6, and this sleeve member is provided with an enlarged index head 12, the under side of which is shaped to engage the guide faces of the arcuate guide 6, the engaging faces being preferably V-shaped as shown. A clamp nut 13 on the sleeve member 11 screws underneath the guide 6 and clamps the sleeve member to the guide, a washer 14 being interposed between the nut and the guide. To the upper end of the spindle 7 is clamped a latch member 15 arranged to engage in calibrated notches 16 in the upper edge of the index head 12, and this latch member may be raised manually and turned to any angle, thereby turning the gem axially to present different facets to the lap, and a flat spring 17 returns the latch to locking engagement with the notch 16 to which the latch is adjusted. A drift pin may be inserted down through the bore in the spindle 7 to remove the arbor from the dop.

The vertical supporting spindle 5 is mounted for free longitudinal movement within certain limits, as will hereinafter appear, in a spindle-supporting block 18, which has an overhanging portion 19 provided with a rounded under side adapted to fit upon an intermediate supporting block 20

having a rounded longitudinal upper edge. This intermediate supporting block 20 is supported upon and has a dovetail engagement with a transversely extending supporting arm 21, which is supported upon the standard 62 at the outer edge of the table 3, as shown in Fig. 1. The intermediate supporting block 20 is, therefore, free to move longitudinally of the supporting arm 21, while the spindle-supporting block 18 is free to move longitudinally of the intermediate supporting block 20 and is supported thereon by the overhanging portion 19, and, since the vertical engaging faces of the two members are of substantial length, the spindle-supporting block 18 will be held firmly by gravity to the intermediate supporting block. The intermediate supporting block is provided near its bottom with a serrated plate 22 having serrations on its under side, and the spindle-supporting block 18 is provided on each side with a plate 23 having a projecting tooth 24 arranged to engage in the serrations in the plate on the intermediate supporting member 20.

The rounded engaging faces between the overhanging portion 19 and the intermediate supporting block 21 permit the gem-holding head to be readily rocked out from the intermediate supporting block and lifted off its support or adjusted longitudinally of the supporting block, the tooth 24 serving to lock the gem-holding head in adjusted position. In the machine shown, the supporting arm 21 extends parallel to the radial line on the lap 1 occupied by the gem 4, and in the movement of the spindle-supporting block 18 along the intermediate block 20 on the supporting arm, the gem 4 is guided in a radial line transversely of the lap. The spindle 5 is normally held by gravity with the gem resting upon the polishing surface of the lap in the position shown in the drawings, and it, therefore, falls down with the gem as the gem is polished off, being free to move longitudinally away from the lap.

To prevent the gem from being polished to too great a depth at any facet, automatic disengaging means are provided, which become operative at the conclusion of the polishing operation upon every facet and the illustrated tripping mechanism for this purpose is an embodiment of my invention described and claimed in my co-pending application, Serial Number 733,418, filed on even date herewith. This disengaging mechanism consists of means for raising the gem holder and gem away from the lap and a trigger for operating this mechanism, which is arranged in the path of the gem upon the lap and is so adjusted that it strikes the lap at a predetermined stage of the polishing operation and is tripped thereby and operates the disengaging mechanism.

An inner spring cup 25 surrounds the spindle 5 and is integral with a micrometer screw 26 formed at its upper end, which ~~coincides~~ with threads on the spindle 5 near its upper end, the upper end of the spindle being calibrated, as shown, to indicate the adjustment of the micrometer screw 26. Telescoping over the inner spring cup 25 and arranged reversely thereto is an outer spring cup 26 and a coiled thrust spring 27 surrounds the spindle 5, and bears at its upper end against the top of the stationary inner cup 25, and at its lower end against the bottom of the slidable outer cup 26, and tends to spread these cups apart, until the bottom of the cup 26 strikes an abutment nut 28 on the screw-threaded upper end of the spindle-supporting block 18, and then the further separation of the cups raises the spindle 5 as far as the crooked lower end of the spindle 5 will permit. The outer slidable cup 26 is, however, normally locked against the tension of the spring 27 by a series of levers, comprising a latch lever 29, a locking lever 30 and a depth-gage trigger 31. To support these levers, a U-shaped lever-supporting member 32 is provided, arranged with its legs horizontal and its base vertical, as shown, and its upper leg is split and provided with a split circular opening arranged to be clamped by clamp screws 33 about the micrometer screw 26, the engaging face of the circular clamp being V-shaped and fitting into a peripheral groove of corresponding shape in the micrometer screw, thereby securely clamping the two parts together against relative movement longitudinally of the spindle 5, while permitting relative rotational movement between the two members. The lower leg of the lever-supporting member 32 is somewhat longer than the upper leg and is pivoted upon the spindle 5 slightly above the crooked lower end, being split and clamped by screws 34 similar to the clamping construction of the other leg. The lever-supporting member is thus supported on the spindle 5 at two points sufficiently far apart to rigidly hold the lever-supporting member in parallelism with the spindle. The base portion of the lever-supporting member is channeled and is provided near its bottom with a lug 35, and the inner end of the locking lever 30 is bifurcated and straddles this lug 35 and is pivoted thereto. This locking lever 30 extends rearwardly through a slot in the bottom of the spindle-supporting block 18, as shown in Fig. 7. The latch lever 29 is pivoted at its lower end to the locking lever 30 near its inner end and extends vertically for the greater portion of its length within the channeled base of the lever-supporting member 32 and is guided near its upper end by a guide 36 extending outwardly from the base of the

channel portion. The latch lever 29 is bent inwardly near its upper end and its end is turned upwardly and is arranged to latch under a flange 37 on a slidable cup member 26. The depth-gage trigger 31 is pivoted at its upper end to the free end of the lower leg of the lever-supporting member 32 and extends down toward the lap and is provided with a locking nose 38 arranged to rest under the downwardly projecting free end of the locking lever 30 and prevents the free end from being forced down and thereby holds the latch lever 29 in locked position and prevents the separation of the two spring cups 25 and 26. When the trigger 31 is rocked upon its pivot, the nose 38 is moved from under the locking lever 30 and the latch lever 29 is therefore free to force down by the tension of the spring 27, and the spring thereupon becomes effective to separate the two cup members and raise the spindle 5 and disengage the gem from the lap. This rocking of the trigger 31 upon its pivot is effected by the engagement of the lower end of the trigger with the lap, 90 the engaging end of the trigger being made arcuate concentric with its pivot so that the trigger is merely rotated and it is pivoted without any tendency to move its pivoted and connected parts. The trigger 31 is arranged to engage the lap at a predetermined time, and thereby determine the depth to which a facet will be polished, and this time of disengagement of the gem by the operation of the trigger 31 is determined by adjusting the micrometer screw 26 longitudinally of the spindle 5, thereby moving the lever-supporting member 32 and the trigger 31 toward and from the lap to the desired adjusted position. 105

The trigger 31 is arranged so that it engages the latch directly behind the gem, as shown, so that it will engage precisely the same path upon the lap that the gem does, and the two will not be differentially affected by unevennesses upon the lap. To adjust the trigger angularly about the gem to bring it into tracking alignment, the lever-supporting member 32 is adjusted upon its pivot angularly about the spindle 5. To hold the lever-supporting member 32 in adjusted position, a spring clamp 39 is provided. This spring clamp is bifurcated and its bifurcated portion surrounds the spindle 5 about an undercut collar portion 40 (see Fig. 3) and at its opposite end the spring clamp 39 is provided with two upwardly projecting fingers 41, which straddle the lower leg of the lever-supporting member 32. This spring clamp 39 is, therefore, 120 locked against movement relative to the lever-supporting member 32, and it engages the collar 40 with sufficient friction to hold the lever-supporting member in adjusted position. To indicate the position of ad- 130

justment, a pointer 42 is provided on the spring clamp 39 which co-operates with a calibrated index plate 43 fixed on the spindle 5 directly above the collar 40. The intermediate supporting block 20 is also correspondingly calibrated, and as the gem-holding head is adjusted longitudinally of the intermediate supporting block 20, the trigger 31 is adjusted until the indication on the index 43 corresponds to the indication on the intermediate supporting block 20, and the trigger is then in tracking alinement with the gem.

To prevent unevennesses on the polishing surfaces of the lap from producing streaks or grooves in the facets of the gem, I provide means for reciprocating the gem transversely of the lap which are normally inoperative and which are thrown into operation near the end of the polishing operation, and these means embody my invention claimed and described in my co-pending application Serial Number 733,417, filed on even date herewith. The illustrated means comprise an electric motor 44, mounted upon a rearward extension of the supporting arm 21, which operates a worm wheel 45, on the shaft of which is provided a crank 46 connected by a pitman 47 with the intermediate supporting block 20, and when this motor is energized, the intermediate supporting block 20, and consequently the gem holder and gem, are reciprocated longitudinally of the supporting arm 21 through this motor-driven means. Supported upon laterally extending arms projecting from the supporting arm 21 is a stationary contact member 48 extending parallel with the supporting arm 21 and of a length substantially equal to that of the supporting block 20, these laterally extending arms, to which the stationary contact 48 is secured, being insulated from the supporting arm 21, as shown in Fig. 3. A movable co-operating spring contact member 49 is carried by the lower leg of the lever-supporting member 32 in position to make contact with the stationary member in any position of adjustment of the gem-holding head. When this movable contact member 49 contacts with its co-operating contact member 48, the motor circuit is completed as follows: from the battery 50, through wire 51, stationary contact 48, movable contact 49 and frame of the machine to wire 52 and the field coils of the motor and wire 53 back to the battery 50. This spring contact 49 is, however, normally held away from its co-operating contact by a contact-controlling trigger 54, also pivoted to the free end of the lower leg of the lever-supporting member 32 by the side of or in radial alinement with the depth-gage trigger 31, the two triggers being thin and so close together that the contact-controlling trigger also engages the lap in the path of

the gem so that it is not differentially affected from the gem by unevennesses upon the lap. This contact lever 54 is provided on its upper end with a disengaging nose 55 arranged so that, in the normal position of the contact-controlling lever 54, this nose engages underneath the spring contact 49 and holds it away from its clamping contact, as shown in Fig. 3. As the contact-controlling trigger 54 engages the lap and is rocked upon its pivot, this nose 54 is removed so that the spring contact is free to close the electric contact and energize the motor. This contact-controlling trigger 54 is slightly longer than the depth-gage trigger 31, so that it engages the lap and initiates the operation of the reciprocatory mechanism a short time before the trigger 31 is tripped and the gem lifted from the lap.

As previously stated, the gem is held by gravity against the lap when the disengaging mechanism is locked. At the beginning of the polishing operation only a point or a relatively small surface is presented to the lap, but as the facet is polished down this area becomes larger and the surface to be polished therefore continually increases during the polishing operation. In order that the facet may be polished with equal rapidity as the area of the facet increases, I provide variable pressure means which serve to assist gravity in pressing the gem against the lap, and exert progressively increasing pressure upon the gem as it is polished down. These means in the illustrated embodiment comprise two weighted bell-crank levers 56 pivoted to opposite sides of the spindle-supporting block 18, and connected by coupling links 57 to radially extending arms 58 on a collar 59 clamped about the micrometer screw 26 just above the upper leg of the lever-supporting member 32. These levers tend to rotate from a vertical toward a horizontal position and thereby draw the micrometer screw 26, and hence the spindle 5, down through the spindle-supporting block 18, and they thereby exert force to press the gem forward against the lap with increasing pressure as they rotate from the vertical position. The parts are so designed that when the gem is first applied to the lap, the spindle is held up in its supporting block to such a position that the weighted levers 56 are substantially vertical and the levers therefore exert a minimum of pressure when the surface of the facet is smallest. As the facet is polished down, the levers 56 rotate toward the horizontal, and since the pressure which they exert increases in proportion to their angle from the vertical, the pressure which they exert upon the gem increases as the gem is polished off and in proportion to the increase in area of the facet. The arbors are made of variable lengths according to the

size of the gem and they are so designed that the facet to be polished is always the same distance from the end of the dop, irrespective of the size of the gem. Consequently the weighted levers 56 are always in a vertical position at the beginning of the operation, irrespective of the size of the gem.

To limit the upward movement of the spindle 5 and connected parts relative to the 10 spindle-supporting member 18, the inner spring cup 25 is provided with two diametrically opposite downwardly extending fingers or projections 60 which project down through slots provided for them in the bottom of the outer slidable spring cup 26, and the lower end of these projections 60 is rounded and provided with a stop nut 61 arranged to engage underneath a shoulder on the abutment nut 28 and thereby limit 20 the upward movement of the spindle 5. As the gem is polished off and the spindle 5 moved down through its support, these stop nuts 61 move away from the shoulder on the abutment nut, and the parts are so arranged 25 that the distance between the bottom of the slidable cup 26 and the top of the abutment nut 28 is always the same when the depth-gage trigger 31 is tripped.

To prevent scratching of the lap when the 30 gem is first presented to the lap, which will result if the gem is pressed too hard against the lap at the beginning of the polishing operation when a point of the gem is presented to the lap, a check device is provided for checking the rapidity of movement of the gem toward the lap. In the illustrated machine, this check device comprises a dash pot, one element of which is connected to one of the weighted bell-crank 35 levers 56 and the other element of which is secured to the plate 23 on flat side of the spindle-supporting block 18. This dash pot is constructed so that the liquid will not spill out in any position in which the head is placed. The lower stationary member comprises a cylinder 63 in which telescopes the valve-carrying cylinder 64, the two being united by a flexible liquid tight cover 65. The bottom of the inner movable telescoping 40 member is closed by a downwardly opening valve 66, which is held against the seat by a spring 67, which opens against the tension of this spring when the movable element is raised, thereby permitting free movement of the gem away from the lap. As the movable element 64 moves in the opposite direction, however, the valve 66 is closed against the seat and movement is retarded. The valve 66 is made integral with a winged 45 plug 67, which serves to guide the valve, and which is provided with a restricted central longitudinal bore 68 communicating with three lateral outlets 69. A screw plug 70 in the bottom of the valve 66 is provided 50 with a groove, which communicates with

the bore 68 and the extent of communication between the two is determined by the adjustment of the screw 70, the upper end of the screw being shaped to cut off communication with the bore 68 when the screw is in its uppermost adjustment. Lateral outlets 70 71 provide communication between the movable element 64 and the flexible covering 65. This flexible covering is secured to the two elements by retaining rings 72.

It is obvious that various modifications may be made in the construction shown in the drawings and above particularly described within the principle and scope of my invention.

I claim:

1. A gem polishing machine comprising a polishing lap, a dop-holding head arranged to hold a gem in engagement with the lap, and variable pressure-applying means arranged to press the gem against the lap with progressively increasing pressure as a facet is polished.

2. A gem polishing machine comprising a polishing lap, a dop-holding head arranged to hold a gem in engagement with the lap, a spindle carrying the dop-holding head and arranged for free axial movement toward and from the lap, and variable pressure-applying means engaging the spindle and arranged to press the spindle axially toward the lap with progressively increasing pressure as a facet is polished.

3. A gem polishing machine comprising a polishing lap, a dop-holding head arranged to hold a gem in engagement with the lap, a spindle-supporting member, a spindle carrying the dop-holding head and mounted in the spindle-supporting member for free axial movement toward and from the lap, and a weighted lever operatively connected to the spindle and spindle-supporting member and arranged to gravitate from a vertical toward a horizontal position as a facet is polished and thereby press the spindle axially toward the lap with progressively increasing pressure.

4. A gem polishing machine comprising a polishing lap, a dop-holding head arranged to hold a gem in engagement with the lap, a spindle-supporting member, a spindle carrying the dop-holding head and mounted in the spindle-supporting member for free axial movement toward and from the lap, and a weighted lever stationarily pivoted on the spindle-supporting member, a link coupling the lever to the spindle, the lever being arranged to rotate about its pivot from a vertical position and draw the spindle through its supporting member toward the lap, thereby applying progressively increasing pressure upon the gem as a facet is polished.

5. A gem polishing machine comprising a polishing lap, a dop-holding head arranged

to hold a gem in engagement with the lap, variable pressure-applying means arranged to press the gem against the lap with progressively increasing pressure as a facet is polished, and a check device operative to control the rapidity of the movement of the gem toward the lap.

6. A gem polishing machine comprising a polishing lap, a dop-holding head arranged to hold a gem in engagement with the lap, a spindle-supporting member, a spindle carrying the dop-holding head and mounted in the spindle-supporting member for free axial movement toward and from the lap, a weighted lever pivotally mounted on the spindle-supporting member and coupled to the spindle and arranged to rotate about its pivot from a vertical position and draw the spindle through its supporting member toward the lap, thereby applying progressively increasing pressure upon the gem as a facet is polished, and a check device operative to control the rapidity of the movement of the gem toward the lap.

25 7. A gem polishing machine comprising a relatively rotary lap, a gem holder arranged to hold a gem in contact with the lap and to approach the lap as the gem is polished, disengaging means arranged when operated to lift the holder from the lap, a depth-gage trigger carried by the holder in the path of the gem upon the lap and arranged in control of the disengaging means and adapted to engage the lap at a predetermined stage of the polishing operation and to be operated thereby to operate the disengaging means, normally inoperative reciprocatory means adapted to reciprocate the gem holder across the lap, and a reciprocatory-means-operating trigger arranged to engage the lap in the path of the gem in radial alinement with the depth-gage trigger and to be operated thereby to render the reciprocatory means operative.

45 8. A gem polishing machine comprising a relatively rotary lap, a gem holder arranged to hold a gem in contact with the lap and to approach the lap as the gem is polished, disengaging means arranged when operated to lift the holder from the lap, a depth-gage trigger carried by the holder in the path of the gem upon the lap and arranged in control of the disengaging means and adapted to engage the lap at a predetermined stage of the polishing operation and to be operated thereby to operate the disengaging means, a normally deenergized electric motor operatively connected to reciprocate the holder across the lap, a contact-controlling trigger arranged to engage the lap in the path of the gem in radial alinement with the depth-gage trigger and to be rocked thereby at a predetermined state of the polishing operation, and normally open electric contacts for the

motor arranged to be closed by the rocking of the contact-controlling trigger and to thereby energize the electric motor.

9. A gem polishing machine comprising a relatively rotary lap, a gem holder arranged to hold a gem in contact with the lap, an electric motor operatively connected to reciprocate the holder across the lap, a source of current therefor, a stationary electric contact, and a co-operative movable contact carried by the gem holder and arranged to make sliding contact with the stationary contact as the gem holder is reciprocated.

10. A gem polishing machine comprising a relatively rotary lap, a gem holder arranged to hold a gem in contact with the lap and to approach the lap as the gem is polished, an electric motor operatively connected to reciprocate the holder across the lap, a source of current therefor, a stationary electric contact, a co-operative movable contact carried by the gem holder and arranged to make sliding contact with the stationary contact as the gem holder is reciprocated, and a contact-controlling trigger carried by the gem holder and arranged to engage the lap at a predetermined stage of the polishing operation and to be rocked thereby and operative to close the electric contacts.

11. A gem polishing machine comprising a relatively rotary lap, a gem holder arranged to hold the gem in contact with the lap and to approach the lap as the gem is polished, a supporting arm for the gem holder extending transversely of the lap, an intermediate supporting block for the gem holder mounted upon the supporting arm for movement longitudinally thereof, the gem holder being adjustable longitudinally of the supporting block, an electric motor operatively connected to reciprocate the supporting block and gem holder longitudinally of the supporting arm, a stationary electric contact for the motor circuit extending substantially the length of the supporting block, a co-operative spring electric contact movable with the supporting block and arranged to engage the stationary contact in any position of the supporting block and close the motor circuit, and a contact-controlling trigger carried by the gem holder and normally holding the spring contact open and arranged to engage the lap at a predetermined stage of the polishing operation and to be operated thereby to release the spring contact and close the motor circuit.

12. A gem polishing machine comprising a polishing lap, a gem-holding head arranged to hold a gem in contact with the lap, a supporting arm for the gem-holding head provided with a serrated portion at its lower edge, and a locking tooth on the gem-holding head arranged to engage the serrated portion of the supporting arm and

- lock the gem holding head against movement longitudinally of the supporting arm, the engaging faces of the gem-holding head and supporting arm, being so shaped that the gem-holding head may be rocked upon the supporting arm to move the locking tooth out of engagement with the serrated portion and thereby release the gem-holding head from the supporting arm.
13. A gem polishing machine comprising a polishing lap, a gem holder arranged to hold a gem in contact with the lap and to approach the lap as the gem is polished, disengaging means arranged when operated to lift the holder from the lap, a depth-gage trigger arranged to engage the lap at a predetermined stage of the polishing operation and to be operated thereby to operate the disengaging means, an angularly movable supporting member for the depth-gage trigger arranged to move the trigger angularly about the gem holder, a spring clamp secured to the angularly movable support and frictionally engaging the gem holder, a pointer on the spring clamp, and a co-operative index on the holder co-operative with the pointer to indicate the angle of adjustment of the depth-gage trigger.
14. A gem polishing machine comprising a polishing lap, a dop-holding head arranged to hold a gem in engagement with the lap, a spindle carrying the dop-holding head and mounted for free axial movement toward and away from the lap, disengaging means operative to move the spindle and dop-holding head away from the lap, a depth-gage trigger arranged to engage the lap at a predetermined stage of the polishing operation and to be operated thereby to operate the disengaging means, and a trigger-supporting member carried by the spindle and adjustable longitudinally thereof and guided thereby.
15. A gem polishing machine comprising a polishing lap, a dop-holding head arranged to hold a gem in engagement with the lap, a spindle-holding member, a spindle carrying the dop-holding head and mounted on the spindle-holding member for free axial movement toward and away from the lap, disengaging means operative to move the spindle and dop-holding head away from the lap, a depth-gage trigger arranged to engage the lap at a predetermined stage of the polishing operation and to be operated thereby to operate the disengaging means, and a U-shaped trigger-supporting yoke member adjustable longitudinally of the spindle and supported thereby at two points spaced by the spindle-holding member, so that these points of support are at a sufficient distance apart to afford a rigid guide for the trigger-supporting member.
16. A gem polishing machine comprising a polishing lap, a dop-holding head arranged to hold a gem in engagement with the lap, a spindle carrying the dop-holding head and mounted for free axial movement toward and away from the lap, disengaging means operative to move the spindle and dop-holding head away from the lap, a depth-gage trigger arranged to engage the lap at a predetermined stage of the polishing operation and to be operated thereby to operate the disengaging means, a micrometer screw on the spindle having a V-shaped peripheral bearing face, and a trigger-supporting member carried by the micrometer screw and provided with a complementary V-shaped annular clamp engaging the peripheral bearing face of the micrometer screw.
17. A gem polishing machine comprising a polishing lap, a dop-holding head arranged to hold a gem in engagement with the lap, a spindle carrying the dop-holding head and mounted for free axial movement toward and away from the lap, disengaging means operative to move the spindle and dop-holding head away from the lap, a depth-gage trigger arranged to engage the lap at a predetermined stage of the polishing operation and to be operated thereby to operate the disengaging means, a micrometer screw on the spindle having a V-shaped peripheral groove, a trigger-supporting member carried by the micrometer screw and provided with a V-shaped annular split clamp engaging in the peripheral groove of the micrometer screw, and clamping means for adjustably clamping the trigger-supporting member about the micrometer screw, the trigger-supporting member thereby being adjustable angularly about the spindle to bring the trigger into the path of the gem upon the lap.
18. In a gem polishing machine, an arcuate supporting guide slotted to provide spaced side parts, and a dop holding head adjustable upon the arcuate guide and comprising a dop, a sleeve member surrounding the dop and extending through the slot in the arcuate guide and provided with a head engaging upon one side of the arcuate guide, and a clamping nut surrounding the sleeve member at the other side of the arcuate guide and operative to clamp the sleeve to the arcuate guide.
19. In a dop-holding-head for gem polishing machines, an arbor-holding dop provided with a tubular dop head, a gem-holding arbor in the dop head provided with a longitudinal groove, a locking member in the dop head arranged to engage in the longitudinal groove and hold the arbor against relative rotation, and means for effecting rotative adjustment of the dop.
20. A gem-polishing machine having, in combination, a polishing-lap, means for holding a gem in engagement with the lap

- to polish the gem, and means for automatically pressing the gem against the lap with a progressively increasing pressure as the facet is worn away.
- 5 21. A gem polishing machine having in combination with a polishing lap means for holding the gem in engagement with the lap to polish the gem, and means for forcing the gem toward the lap with increasing pressure as the polishing proceeds.
- 10 22. A gem-polishing machine having, in combination, a movable polishing-lap, a supporting arm, a gem-holding head adjustable longitudinally of said arm parallel to the polishing-lap, means for locking said head in adjusted position on said arm, and means for automatically moving said supporting arm back and forth in a line parallel to the surface of the lap while the gem is being polished.
- 15 23. A gem-polishing machine having, in combination, a moving polishing-lap, a gem-holder for holding the gem in contact with the lap, means for removing the gem from the lap, means having a member adapted to engage the lap in the path of the gem for causing said removing means to remove the gem from the lap at a predetermined stage in the polishing operation, means for moving the gem back and forth over the lap, and means having a member adapted to engage the lap in the path of the gem for causing said moving means to move the gem back and forth at a predetermined stage in the polishing operation.
- 20 24. A gem-polishing machine having, in combination, a moving polishing-lap, a gem-holder for holding the gem in contact with the lap, means for removing the gem from the lap, means having a member adapted to engage the lap in the path of the gem for causing said removing means to remove the gem from the lap at a predetermined stage in the polishing operation, and means for adjusting the distance of said member from the lap relative to the distance of the gem-holder from the lap.
- 25 25. A gem-polishing machine having, in combination, a moving polishing-lap, a gem-holder for holding a gem in contact with the lap, means for moving the gem back and forth over the lap, means having a member adapted to engage the lap in the path of the gem for causing said moving means to move the gem back and forth at a predetermined stage in the polishing operation, and means for adjusting the distance of said member from the lap relative to the distance of the gem-holder from the lap.
- 30 26. A gem polishing machine having in combination with a polishing lap means for holding the gem in engagement with the lap to polish the gem, and means for forcing the gem toward the lap with increasing pressure as the polishing proceeds, said last
- mentioned means comprising a weighted lever.
27. A gem polishing machine having in combination a polishing lap, means for holding the gem in engagement with the lap to polish the gem, means for forcing the gem toward the lap with increasing pressure as the polishing or grinding proceeds and means for checking or damping the movement of the gem toward the lap.
- 75 28. A gem polishing machine having in combination a polishing lap, a gem holder for holding the gem in contact with the lap, means for forcing the gem toward the lap with a gradually increasing pressure during the polishing, means for checking or damping the movement of the gem toward the lap, a supporting means for the gem holder, means whereby the gem holder may be adjusted on said supporting means to bring the gem onto different polishing bands of the lap, and means for reciprocating the gem laterally over the lap during the polishing or grinding of the gem.
- 80 29. A gem polishing machine having in combination a polishing lap, a gem holder for holding the gem in contact with the lap, a supporting means for the gem holder, means whereby the gem holder may be adjusted on said supporting means to bring the gem onto different polishing bands of the lap and means for reciprocating the gem laterally over the lap during the polishing or grinding of the gem.
- 85 30. A gem polishing machine having in combination a polishing lap, a gem holder for holding the gem in contact with the lap, means for forcing the gem toward the lap with a gradually increasing pressure during the polishing, a supporting means for the gem holder and means whereby the gem holder may be adjusted on said supporting means to bring the gem onto different polishing bands of the lap.
- 90 31. A gem polishing machine having in combination a polishing lap, a gem holder for holding the gem in contact with the lap, means for automatically withdrawing the gem from the lap when the polishing operation has reached a predetermined stage, a supporting means for the gem holder, means whereby the gem holder may be adjusted on said supporting means to bring the gem onto different polishing bands of the lap, and means for reciprocating the gem laterally over the lap during the polishing or grinding of the gem.
- 105 32. A gem polishing machine having in combination a polishing lap, a gem holder for holding the gem in contact with the lap, means for forcing the gem toward the lap with a gradually increasing pressure during the polishing, a supporting means for the gem holder, means whereby the gem holder may be adjusted on said supporting means
- 110 120 125 130

to bring the gem onto different polishing bands for the lap, and means for automatically withdrawing the gem from the lap when the polishing operation has reached 5 a predetermined stage and a trip device for causing said withdrawing means to operate.

33. A gem polishing machine having in combination a polishing lap, a gem holder for holding the gem in contact with the lap, 10 means for forcing the gem toward the lap with a gradually increasing pressure during the polishing, means for automatically withdrawing the gem from the lap when the polishing operation has reached a predetermined stage and means for reciprocating the gem laterally over the lap during the polishing or grinding of the gem.

34. A gem polishing machine having in combination a polishing lap, a gem holder 20 for holding the gem in contact with the lap, means for forcing the gem toward the lap with a gradually increasing pressure during the polishing, and means for automatically withdrawing the gem from the lap when the 25 polishing operation has reached a predetermined stage and a trip device for causing said withdrawing means to operate.

35. A gem polishing machine having in combination with a polishing lap means for 30 holding the gem in engagement with the lap to polish the gem while permitting movement of the gem toward and from the lap, and damping means for checking or retarding the movement of the gem toward 35 the lap.

36. A gem polishing machine having in combination with a polishing lap means for holding the gem in engagement with the lap to polish the gem while permitting 40 movement of the gem toward and from the lap, damping means for checking or retarding the movement of the gem toward the lap, and means whereby the damping means does not retard the movement of the gem 45 away from the lap.

37. A gem polishing machine having in combination with a polishing lap means for holding the gem in engagement with the lap

to polish the gem while permitting movement of the gem toward and from the lap, means for withdrawing the gem from the lap, and damping means for checking or retarding the movement of the gem toward the lap.

38. A gem polishing machine having in 55 combination with a polishing lap means for holding the gem in engagement with the lap to polish the gem while permitting movement of the gem toward and from the lap, means for withdrawing the gem from the 60 lap, damping means for checking or retarding the movement of the gem toward the lap, and means whereby the damping means does not retard the movement of the gem 65 away from the lap when withdrawn by said withdrawing means.

39. A gem polishing machine having in combination, a rotary polishing lap, a supporting arm extending over the lap substantially parallel to the polishing surface 70 thereof, a gem holder adjustable parallel to the polishing surface of the lap on said arm to bring the gem onto different polishing bands of the lap, and means whereby the gem holder may be moved relatively to said 75 arm toward and away from the polishing surface of the lap in a line at right angles thereto.

40. A gem polishing machine having in combination, a rotary polishing lap, a supporting arm extending over the lap substantially parallel to the polishing surface 80 thereof, a gem holder adjustable on said arm to bring the gem onto different polishing bands of the lap, means whereby the 85 gem holder may be moved toward and away from the polishing surface of the lap, and means for automatically withdrawing the gem from the lap when it has been polished to a predetermined extent.

In testimony whereof I have affixed my signature in presence of two witnesses.

CLYDE J. COLEMAN.

Witnesses:

VICTOR D. BORST,
WM. A. KELLY.

It is hereby certified that in Letters Patent No. 1,173,175, granted February 29, 1916, upon the application of Clyde J. Coleman, of New Rochelle, New York, for an improvement in "Gem-Polishing Machines," errors appear in the printed specification requiring correction as follows: Page 8, lines 97 and 120, claims 29 and 31, before the word "reciprocating" insert the word *independently*; page 9, line 76, claim 39, for the word "twoard" read *toward*; and that the said Letters Patent should be read with these corrections therein that the same may conform to the record of the case in the Patent Office.

Signed and sealed this 11th day of April, A. D., 1916.

[SEAL.]

Cl. 51—11.

R. F. WHITEHEAD,
Acting Commissioner of Patents.
